SELF-SUSTAINING SCAFFOLD

Edward Baylis Brittin, Washington, D. C.

Application December 6, 1951, Serial No. 260,167

8 Claims. (Cl. 304—2)

1

This invention relates to a self-sustaining scaffold of the knockdown type wherein the main framework thereof is comprised of members formed from wood. This main framework includes a series of superimposed longitudinally extending members known in this art as trestle boards which are maintained in a vertically spaced relation by means of several stages of trestles which are well known in this art.

The invention relates more specifically to a novel form of bracing means that functions to retain all of the stages of the scaffold firmly bound together to form a self-sustaining unit that has a high degree of rigidity and which affords a high degree of safety to the workmen using the same.

It has been a common practice in this art to erect, more or less loosely, a series of vertically spaced trestle members and trestle boards, the lowermost of the series being supported say directly on the ground. After the first stage of trestles has been arranged on the ground or other support, a number of trestle boards are laid across the cross boards of the trestles to permit use thereof as a platform. To provide a platform at a higher elevation, a second stage of trestles are set up upon the outer two trestle boards and the more central trestle boards are removed and used to assemble the second and higher platform. Possibly, the weight of the workmen and materials such as bricks might give a little rigidity to such a scaffold but there are several elements of danger associated with the same. It is possible for the trestles to creep relatively to each other. Then if one outer side of the platform is overloaded, the upper trestles would tend to tilt in the direction of that side and, if say four to seven stages were in use, the entire structure would tend to buckle and collapse. In some cities, an ordinance provides that such scaffolds be limited to as low as two stages hence there is little competition between the wooden and the metal scaffolds in such cities even though the wooden scaffold usually costs about one third as much as a metal scaffold and can be erected in much less time. The danger of lateral collapse of the old form of wooden scaffold is so great that it is common practice to apply long expensive wooden props or braces between the ground and the top of the scaffold to maintain same towards the wall being erected.

The main object of this invention is to provide a novel form of bracing means of the tension type that serves to firmly bind all frame-

2

work members and stages together in a manner to produce a self-sustaining scaffold unit that has a maximum of rigidity and safety.

Another important object is to provide a series of tension brace members that may be quickly placed in position and adjusted and which include quick release members of the hook type that permits a quick knockdown of the scaffold unit.

10 A further object is to provide a braced unitary scaffold that is economical to manufacture, that has a high degree of safety and one which may be assembled in a minimum of time.

15 A further object is to provide a novel form of brace that may be applied at several similar positions in the scaffold to produce a self-sustaining unit.

20 A further object is to provide a scaffold that may be interchangeably arranged to serve as a portable unit carried by caster wheels or one to be supported directly upon a base but with the caster wheels shifted to another position.

25 Other objects will become apparent from the detailed description of the invention which follows.

In the accompanying drawings:

Fig. 1 is a view in front elevation of a three stage self-sustaining scaffold showing the braces in position.

30 Fig. 2 is an end view of a two stage scaffold showing the braces in detail.

Fig. 3 is a view in section taken on line 3—3 of Fig. 2.

35 Fig. 4 shows a specific hook which is a part of the brace.

Fig. 5 shows in perspective a modified form of leg support or base and which is of the portable type, and

40 Fig. 6 is a view of two trestles showing the bracing.

Referring to the drawings in detail, Fig. 1 shows three stages 1, 2, and 3 of a scaffold erected and braced according to this invention. Each trestle unit comprises the usual cross beam 4 having legs 5 that engage the brackets 6. The legs of the lowermost stage rest upon the planks 7 that, in turn, are supported directly upon the ground or upon a series of blocks 8. Fig. 1 shows the trestle legs of all trestles as 2 and 3 above the first stage 1 as being supported upon the trestle boards 9. If elements 7 and 9 are relatively short, several aligned planks may be used overlapped as shown in Fig. 1 for the trestle boards 9.

55 Elements 1 to 9 just described are in common

use and, collectively, have comprised a complete scaffold and no special brace means has been employed up to the present time. Such a scaffold is rather flimsy particularly when three or more stages are used. When a heavy load is placed upon the platform with workmen in action, its instability is evidenced by vibrations therein. If one end of the scaffold is loaded more heavily than the other end, the less loaded end becomes rather loose thereby permitting displacement of parts, these and other objections greatly increase the dangers inherent in the use of such a loose type of scaffold as compared to the metal scaffold.

Fig. 2 shows the novel brace used and its specific locations. While many brace elements are used in the structure, all of the braces are similar that are used to bind together adjacent superimposed trestles. The legs of the lowermost stage are provided with a specific type of base support and a modified form of brace may be used therewith. In one form of such base support, the same brace is used as is applied thereabove between the trestles, hence all braces may be interchangeable.

In Fig. 2, the braces that are used to merely bind the base support planks or sleepers 7 comprise a strap loop 10 that is connected to a terminal eye 11 by a cross bolt or pin. This eye engages a quick detachable hook 12 the lower end of which is threadably engaged with a turnbuckle 13. The lower threaded rod of this turnbuckle passes through the plank 7 and is retained by a nut 14. A slip ring 15 encircles the strap loop for a purpose to be described.

The main binding braces that engage the cross beams of the trestles comprise each a strap 10 and slip ring 15 connected to a turnbuckle 16 which has a screw eye or hook 17 that connects to the strap 10. The hook 12 comprises a threaded rod 18 that forms a part of the turnbuckle. A second strap 19 is connected to a ring 20 that is adapted to engage the hook 12 and a slip ring 21 encircles the strap loop 19.

Fig. 5 shows the modified form of base support and portable scaffold. All braces used with this form are similar including the single brace connected to the central portion of the base support 22. These supports 22 carry planks 7-7' that carry the scaffold load. The lower loop 19 encircles the support 22 and the latter support serves also as a brace anchor so that these supports may be bound to the trestle stages as a unit, in the position shown, these casters render the scaffold mobile or portable. If mobility is not desired, the transverse members 22 may be rotated a quarter turn so that the casters will project laterally free of the ground.

The hook 12 in Fig. 4 has a pivoted section 25 the weight of which is distributed so as to cause or permit this section to fall by gravity, after the ring 26 has been displaced upwardly, to a position shown by the dotted lines where it remains to more readily permit an eye ring as 28 to be engaged thereon. Obviously, as shown, upon closure of this section 25, the engaged ring will be raised in a manner to pull up on or tighten the attached loop 19 as well as the upper loop 10.

The mode of erecting the main elements of the scaffold does not differ from that now in common use but it is important to understand the application and operation of the various braces. When any cross beam 4 is applied, a strap loop as 18 or 19 is slipped over this board and the opposed loops 10 and 19 are connected, respectively, to

the eye 17 and the hook 12 that forms a unit with a turnbuckle element 16.

The function of slip links or rings 15 and 21 is important and novel in the relation shown, reference being made to Fig. 3 which shows a ring 15 that has been moved upwardly over the loop 10. Such movement acts to pull the opposed sides of the loop towards each other which causes an appreciable tightening of this loop and actually acts to cause the strap loop to pull downwardly on a cross beam 4. Likewise, the loop 19 will act to pull up on the opposed beam 4 when the ring 21 is moved towards this beam.

Such coaction of these two brace tightening forces, that is the tightening action of the hook and that due to the shortening of loops, will take up all slack in each brace and will actually act to pull an opposed pair of beams 4 together. Thereafter, the turnbuckle 16 is tightened and each superimposed pair of trestles will be bound together axially with a force up to 1000 pounds or more.

In effect, each series of superimposed trestles actually function as a rigid vertical pylon or beam element sufficiently rigid to render it impossible under any normal or even under an abnormal work load or lateral stress to cause such element to buckle. In effect, each vertically spaced series of trestles thus bound together functions as a built up beam which could be called a back-bone and the entire scaffold unit becomes built up to include several back-bone elements, one for each vertical series of trestles. It should be noted, also, in Fig. 1 that all overlapped trestle boards as at 9 become rigidly bound together at their adjacent ends thereby to prevent any lateral slippage between adjacent trestle units.

Referring to Fig. 3, the loop 10 in the metallic strap, is slid over a cross beam to its central portion and then subjected to its tension loading, after the slip ring has been pushed towards the beam to partly close the loop. This causes the loop to cut into the wooden beam and produce rounded depressions at the corners thereof contacted by the loop. These depressions serve the useful purpose of enabling the erector to replace all loops during reassembly at the same positions before occupied by these loops, and no further marring occurs.

It will be noted that, by use of the specific brace used and the flat strap loop connectors, the cross beams of each trestle need not be marred nor weakened by cutting or drilling. The strap loops are easily bent and they may be opened up some to permit a ready removal from the beams.

When the scaffold is unloaded, after a first erection, there is not sufficient weight available to force the tapered ends of the legs into the brackets. As shown in Figs. 2 and 6, the brackets 6 are tapered along both their narrow and their wide sides, hence each leg must be formed at one end with corresponding tapers. With no braces used, the structure would be wobbly, that is, too loose. However, according to the present invention, when the braces are tensioned, the tapered leg ends will be forced into the brackets and become securely held therein to permit the trestle to be moved as a unit for a next re-assembly. Since after say one or two stages have been erected and properly tensioned by the braces, when the trestle boards are slid into position upon the uppermost trestle cross beams, if any board

were to strike a cross beam, that beam and trestle would not become displaced.

A main defect of a loosely set up scaffold is that certain trestles actually shift as a job progresses and such shifting is known as "walking" by the workmen thereon. It is possible for a trestle to actually slip from the supporting board 7. However, due to brace tension, all trestles and board elements are firmly bound together and all trestle shift is prevented.

In the event that any one leg of a trestle is shorter than the other legs, a common occurrence in such scaffolds heretofore used particularly after much usage, such scaffolds become unstable. However, the force of the braces acting downwardly on the cross beams will force any shorter leg down firmly against a supporting board 7 upon which the trestle is mounted thereby providing greater stability and preventing any relative shifting of positions of the trestles with respect to the associated longitudinally extending board elements.

In view of this disclosure, it will become obvious that the scaffold as described will possess a maximum of rigidity to withstand possible collapse. It will provide a maximum of safety, can be erected very quickly and will be economical to manufacture and maintain.

It is to be understood that the equivalents of elements shown are contemplated within the scope of the appended claims.

I claim:

1. A self-sustaining scaffold comprising a lowermost stage of spaced trestles, each trestle consisting of a transverse beam and a plurality of legs secured thereto for supporting the beam, the adjacent trestles being positioned in parallel relation, a plank element positioned upon said transverse beams adjacent each end thereof, a second stage of trestles supported upon said plank elements in a manner to position the transverse beam of each trestle in the second stage directly above and parallel to a corresponding beam of the first stage of trestles; means for binding said stages together, said means comprising a vertically extending tension brace for interconnecting each vertically spaced pair of beams; each brace comprising an adjustable coupling, said coupling including a member manually movable to vary the length of the coupling, a tension member extending from each end of the coupling, the free end of each tension member being connected to a respective transverse beam whereby the coupling may be operated to pull the pairs of opposed transverse beams together and rigidly bind together both stages of trestles.

2. A self-sustaining scaffold comprising a first series of laterally spaced trestles, each trestle comprising a transverse beam supported by legs, said beams being positioned in a parallel relation, trestle boards positioned across said beams; a second series of laterally spaced trestles supported upon said boards, each beam in the second stage being positioned directly above a corresponding beam of the first stage; means for rigidly binding said stages together and firmly against said trestle boards; said means comprising a series of similar vertically extending tension braces, each beam of the first series being connected to a corresponding beam of the second series thereabove by one of the series of braces; each brace comprising a turnbuckle and a tension member connected to each end of the turnbuckle, the free ends of the tension members being connected respectively to adjacent transverse

beams, whereby operation of the turnbuckle functions to pull the vertically spaced transverse beams towards each other to bind the stages rigidly together.

5 3. A scaffold as set forth in claim 2 wherein the tension members connected to the turnbuckles comprise a metallic strap loop, said loop surrounding the transverse member engaged thereby.

10 4. A scaffold as set forth in claim 2 wherein the tension members connected to the turnbuckles comprise a metallic strap loop, said loop surrounding the transverse beam engaged thereby; a slip ring positioned to surround each strap loop and being slidable towards the adjacent transverse beam to constrict and shorten said loop thereby to take up slack in the respective brace.

15 5. A scaffold as set forth in claim 2 wherein the tension members connected to the turnbuckles comprise a metallic strap loop, said loop surrounding the transverse beam engaged thereby, 20 one of said tension members having a terminal eye and being detachably connected to the turnbuckle by means of a hook, said hook comprising a shank portion connected to the turnbuckle and an arcuate load supporting finger pivoted to the free end of the shank portion, a retaining ring encircling said shank portion and being adapted to engage the free end of the finger, said finger engaging the terminal eye whereby, when the ring is disengaged from the finger, the latter is free to swing and be disengaged from the eye.

25 6. In a scaffold as set forth in claim 2 wherein the legs of the first series of trestles are supported upon relatively wide plank members, tension rods secured to the plank members at points located between each pair of legs and substantially below each end of a respective transverse beam, tension braces interconnecting each tension rod to the adjacent end of the respective transverse beam, and adjustable means for tightening said braces whereby the plank members are pulled upwardly to rigidly engage the legs of the first series of trestles.

30 7. In a scaffold as set forth in claim 2 wherein the legs of the first series of trestles are supported on relatively wide plank members, said plank members being, in turn, supported upon a series of transversely arranged base forming members, each base member being positioned directly below a respective transverse beam, a series of adjustable tension braces, each brace being connected at one end thereof to a transverse beam and at its other end to a base member therebelow substantially at the center thereof, adjustable means for tightening said braces whereby upon adjustment of said means, the transverse beams of the first series of trestles will be pulled downwardly to rigidly bind the scaffold to the base members.

35 8. In a scaffold as set forth in claim 2 wherein the legs of the first series of trestles are supported on relatively wide plank members, said plank members being, in turn, supported upon a series of transversely arranged base forming members, each base member being positioned directly below a respective transverse beam, a series of tension braces for binding the transverse beams of the first series of trestles to the base members, each last named brace being connected at its upper end to a respective transverse beam and having a terminal loop connector at its lower end to be engaged around a respective base member, a series of caster wheels secured to one side of each base member and, in one position, being adapted to engage the ground, said terminal loop connector serving to permit the base members to

be rotated to a second position in which the caster wheels are retained free from ground contact.
